IMAGE SUPPRESSION IN SUPER-HETERODYNE RECEIVERS

Frederick H. Scheer, Kenmore, N. Y., assignor to
 Colonial Radio Corporation, Buffalo, N. Y., a
 corporation of New York

Application October 1, 1941, Serial No. 413,170

13 Claims. (Cl. 250—29)

This invention relates to radio receiving apparatus and more particularly to signal selecting circuits for superheterodyne receivers.

In such receivers, as is well known, the intermediate frequency amplifier stage or stages are tuned to a frequency above audibility and usually below the lowest frequency of the broadcast band. Present practice is to tune the intermediate frequency stages to 455 kc. in broadcast receivers. Incoming radio frequency signals are heterodyned or "beat" with an oscillation produced by the local oscillator. This gives rise to oscillations of a frequency which may be either the sum or the difference between the incoming frequency and that of the local oscillator. Only those oscillations thereby produced which have a frequency which enables them to pass through the intermediate frequency amplifier are then amplified.

For example, if the intermediate frequency amplifier is tuned to 455 kc. and a 540 kc. signal is being received and the local oscillator has, when this particular signal is being received, a frequency of 995 kc., then there will be produced a "beat" frequency of 455 kc. after detection by the action of the oscillation on the desired signal. However, if there is also an incoming signal of 1450 kc., at the same time, a new oscillation will be produced by the heterodyne action between the local oscillation and the 1450 kc. signal. This new oscillation will, likewise, have a frequency of 455 kc. and will, accordingly, pass through the intermediate frequency amplifier, resulting in interference and cross talk with the desired signal. The frequency of the undesired signal is termed the "image" frequency and it is equal to the frequency of the desired signal plus twice the intermediate frequency.

It is usual to provide a signal selecting circuit in advance of the first detector in a superheterodyne and this circuit is ordinarily designed to be tuned to the frequency of the desired signal. However, when such a circuit is used, image interference may still be encountered and it has been proposed in the past to eliminate or reduce this image interference by providing preselecting circuits and the like and also by providing one or more wave traps associated with the antenna and variably tuned.

The employment of wave traps for image suppression according to the prior art increases the cost of the receiver since it is necessary to provide an additional coil and an additional condenser, one or the other of which is usually variable. The provision of such additional parts increases the cost of the receiver from the standpoint of materials and parts employed and also the labor of assembling.

In accordance with the co-pending application of Howard J. Benner, Serial No. 239,788, filed November 10, 1938, it is pointed out that it is pos-

sible to provide a simple tuning circuit with only one variable tuning reactance which acts simultaneously as a selector of desired frequency and as an image suppressor; that is to say, the variation of the variable reactance causes the circuit to select the desired signal and at the same time to present an extremely high effective impedance to the image signal. In the circuit of the aforesaid Benner application it is pointed out that there may occur a certain amount of "mistracking" between the signal tuning and the image tuning. This "mistracking" is due to the fact that the 9-1 variation of inductance in the tuned circuit, which is necessary to cover the 3-1 frequency range usually required in a broadcast receiver, also varies the image tuning in a 3-1 frequency ratio.

In the example above given with the signal selector tuned to 540 kc. the image frequency is 1450. With the receiver tuned to 1500 kc. the image frequency is 2410 kc. However, in the Benner circuit above referred to, if the receiver is tuned to 1500 kc., the image suppressor would be tuned to 4028 kc. instead of 2410, the true image frequency; that is to say, as the receiver is tuned from 540 to 1500 kc., the tuning of the image suppressor circuit increases too rapidly. In most cases this is not a serious matter because the worst image interference is usually found when the receiver is tuned to the low frequency end of the broadcast band and the image suppressor may be "peaked" so that it is properly tracked when the receiver is tuned to the low frequency end of the broadcast band.

However, in case this departure from the theoretical value of the image suppressor is desired to be reduced or eliminated, I have discovered that it may be done very easily and effectively without the use of additional coils or variable condensers.

Among the objects of my invention are:

To provide an image suppression circuit which does not require separate wave trap or preselector circuits and in which the image suppressor circuit may be made to track very exactly with its theoretical value.

To provide such a circuit which does not require the employment of additional coils or variable condensers as ordinarily employed.

Still another object of my invention is to provide such a circuit in which the image circuit may be made to track very closely with its theoretical value by the employment of a conducting plate which may be mechanically connected with the tuning mechanism and moved into position adjacent the input coil as the iron core customarily used in permeability tuning is moved out of the coil.

Still other objects and advantages of my invention will be apparent from the specification.

In this application I have particularly pointed out and distinctly claimed the part, improvement, or combination which I claim as my invention or discovery, and I have explained the principles thereof and the best mode in which I have contemplated applying those principles so as to distinguish my invention from other inventions. In the drawings:

Figure 1 is a circuit diagram of one form of circuit in accordance with my invention.

Figure 2 is a set of curves, showing the variation of capacity necessary to keep the image tuning exactly tracked.

Figure 3 is a plan view of the tuning mechanism including coil, core, capacity plate or sleeve, and driving cord; and

Figure 4 is a developed view of the capacity plate employed.

Referring now more particularly to Figure 1, 1 designates the antenna of a superheterodyne receiver which may be connected to ground through antenna coupling condenser 2. The antenna coil 3 may be tuned by core 4 of magnetic material which may be moved into and out of the coil 3. Such cores may be satisfactorily formed of iron dust mixed with a suitable insulating and binding material and pressed or otherwise processed to form what appears as a solid bar. Since such cores are easily obtainable on the market and their construction is per se not a part of my invention, they are not described in detail.

The antenna 1 may be connected to one end of the coil 3, the other end of which may be connected to the control electrode of detector or amplifier tube 7. AVC resistor 11 may be employed in any suitable automatic volume control circuit. Connected from the grid side of the coil 3, I may provide condenser 6 to ground and this condenser may be the usual high frequency trimmer ordinarily employed for aligning the receiver. The cathode of tube 7 may be connected to ground through suitable resistance 12 bypassed by condenser 13.

If the core 4 is moved axially into and out of coil 3, there will be observed a variation in the inductance of coil 3 and a variation of the resonant frequency of the circuit of the input circuit as a whole. By moving the core 4 in and out of the coil the receiver can be tuned to the desired signal.

With most cores and coils commercially available, intended to cover the broadcast range, the frequency of signal tuning is not a straight line function of core movement. This will be seen by reference to dot and dash curve A of Figure 2, showing signal frequency in kilocycles plotted against core travel in inches, and it will be observed that as the core is withdrawn from fully inserted position, the frequency increases quite slowly at first, then more rapidly, reaching a maximum rate of increase, and then decreases more slowly.

The image frequency of course is another curve parallel to curve A and displaced vertically above it by twice the intermediate frequency, and the actual image frequency to which coil 3 and condenser 5 are tuned may be arranged by trimming or adjusting condenser 5 to coincide with the true image frequency at any point on the tuning range desired. Preferably, however, this is done at or near the low frequency end of the range; and if this is done, the resonant frequency of the image suppressor formed by coil 3 and condenser 5 increases at a

faster rate than desired, as already pointed out.

I have found that this increase can be prevented without the use of additional cores or condensers by providing a conducting plate, such as shown in Figure 3, which may be in the form of a sleeve, and which moves into or over the coil as the core is moved out of the coil. This sleeve 15 may be tied to the core mechanically and arranged to be moved by the same mechanism which moves the core for tuning, such as cord 16, which may be attached to the sleeve 15 at the end remote from the coil by plug 16a. It is possible for any given value of inductance 3 and capacity 5, which may be either a physical condenser in parallel with the coil 3 or may be the distributed capacity of the coil 3, to calculate the additional capacity required at any setting of the core to make the image suppressor track exactly at its theoretical value.

Assuming it is desired to cover a signal range of 540 to 1620 kc., it is seen immediately that this frequency range squared is equal to 9 and, therefore, the inductance at 540 kc. must be 9 times that at 1620 kc. The image frequency at 1620 kc. is 2530 kc., and that at 540 is 1450, assuming an intermediate frequency of 455 kc. The ratio of image frequency change squared is equal to 3.05. For a signal frequency of 540 the constants of the circuit made up by coil 3 and capacity 5 are given by the equation

$$f_1 \text{ image} = \frac{1}{2\pi\sqrt{L_1 C_1}}$$

where L_1 is the inductance of coil 3 with the core fully inserted and C_1 the value of capacity 5.

At any higher frequency the constants are given by equation

$$f_2 \text{ image} = \frac{1}{2\pi\sqrt{L_2(C_1 + \Delta C)}}$$

where ΔC represents the additional capacity introduced in parallel with capacity 5 by the sleeve 15. Solving for ΔC in terms of C_1 it is found that $\Delta C = 1.96 C_1$ for a signal frequency of 1620. ΔC may be calculated for any frequency between the lowest and highest. The following table shows the calculation of values for a series of frequencies.

$$\Delta C = C_1 \left[\left(\frac{f_1}{f_2} \right)_{\text{image}} \frac{L_1}{L_2} - 1 \right]$$

$L_1 > L_2$

$f_2 > f_1$

C_1 = original capacity necessary to tune anti-resonant circuit to image frequency.

55	(1)	(2)	(3)	(4)	(5)	(6)
550	$\frac{L_1}{L_2} - \left(\frac{f_1}{550} \right)^2$	Image f_2	$\left(\frac{1460}{f_2} \right)^2$	$(2) \times (4)$	$\frac{\Delta C}{C_1}$	
600	1	1460	1	1	0	
600	1.190	1510	.935	1.113	0.113	
800	2.12	1710	.728	1.543	0.543	
1000	3.31	1910	.584	1.931	0.931	
1200	4.76	2110	.478	2.253	1.253	
1400	6.47	2310	.400	2.588	1.588	
1600	8.45	2510	.338	2.852	1.852	
1750	10.10	2660	.3015	3.045	2.045	

Plotting $\Delta C/C_1$ for the various frequencies calculated, as shown by curve A, gives curve B (full line). Comparing curve B with curve C (dotted) which is the capacity increase which would be obtained if the sleeve 15 were a cylinder (not closed at its seam to prevent acting as a short circuited turn) extending the full length of the coil when moved into position, it will be seen

that the capacity increase required to track the image circuit exactly is considerably less than linear at the beginning; that is, the capacity should increase rather slowly at first. Thereafter it begins to increase at a faster rate and continues to increase at a faster rate until about 1650 kc. and thereafter should increase more slowly. This manner of capacity change may be simply provided by cutting the plate 15 as shown in Figure 4 and thereafter rolling it into the form of a cylinder as indicated in Figure 3 and arranging it to move into the coil as indicated in Figure 3 so that the spread end of the sleeve enters the coil first.

The exact diameter of the sleeve and the clearance between the sleeve and the coil and the angle of taper of the sleeve before rolling may best be determined by trial, using a series of cardboard cylinders of different diameters coated with foil, the foil being cut away by trial and the image ratio being measured to determine the maximum image ratio at a series of chosen frequencies. The maximum image ratio will occur when the image suppressor circuit, consisting of coil 3 and capacity 5, is exactly tuned to the theoretical image value. After the optimum diameter and taper has been determined, the foil may be unrolled and used as a pattern or template for the sleeve 15 in case quantity production is desired. The sleeve may be made of any suitable material, such as copper or aluminum.

For all ordinary values of inductance 3 and capacity 5 encountered in the design of broadcast receivers the effect of the sleeve 15 on the tuning of the signal circuit is for all practical purposes negligible, although, if the circuit is trimmed by the high frequency trimmer 6 before the addition of the sleeve 15, it may be necessary to slightly readjust trimmer 6 after sleeve 15 has been added.

In some cases, where it is desired to have the sleeve 15 introduce a larger capacity than is obtainable with minimum clearance between the sleeve and the coil 3, the sleeve 15 may be connected electrically to the grid end of coil 3.

While I have shown and described certain preferred embodiments of my invention, it will be understood that modifications and changes may be made without departing from the spirit and scope of my invention.

I claim:

1. An image suppression system for superheterodyne radio receivers having an antenna and a vacuum tube with a control electrode, including a first resonant circuit, a portion of which is connected between said control electrode and ground; and a second resonant circuit in series between said antenna and said control electrode, said resonant circuits having a common variable inductance and being tuned respectively to a signal frequency and to the corresponding image frequency; and a conducting plate movable with respect to said inductance to vary the distributed capacity thereof, said plate being arranged to increase the distributed capacity of said inductance as the inductance is reduced.

2. An image suppression system for superheterodyne radio receivers having an antenna and a vacuum tube with a control electrode, including a first resonant circuit, a portion of which is connected between said control electrode and ground; and a second resonant circuit in series between said antenna and said control electrode, said resonant circuits having a common variable inductance device comprising an inductance coil

and a ferro-magnetic core movable relatively thereto and being tunable simultaneously over substantially different frequency ranges by motion of said core; and a conducting plate movable with said core relatively to said coil to change the distributed capacity thereof, said plate being arranged to increase the distributed capacity of said coil as the inductance is reduced.

3. An image suppression system for superheterodyne radio receivers having an antenna and a vacuum tube with a control electrode including a first resonant circuit, a portion of which is connected between said control electrode and ground; and a second resonant circuit in series between said antenna and said control electrode, said resonant circuits having a common variable inductance device comprising an inductance coil and a ferro-magnetic core movable relatively thereto; and a conducting plate movable with said core relatively to said coil to vary the distributed capacity thereof and being movable in a direction to increase the distributed capacity thereof with reduction of the inductance thereof, said resonant circuits being simultaneously tuned by motion of said core and said plate to a signal frequency and to the corresponding image frequency.

4. A preselector system for superheterodyne radio receivers including a variable inductance comprising an inductance coil, a movable ferro-magnetic core, and a movable conducting plate, said core and said plate being so arranged that said plate approaches said coil as said core is withdrawn therefrom, first and second capacitors connected with said inductance device to secure resonance within a first range of frequencies by movement of said core; and a third capacitor in shunt with said inductance device to secure resonance within a second range of frequencies by movement of said core, said capacitors being so chosen that any frequency of said second range is higher than the corresponding frequency of the first range by a practically constant amount throughout said core movement.

5. A preselector system for superheterodyne radio receivers including a variable inductance device comprising an inductance coil, a movable ferro-magnetic core, and a movable conducting plate arranged to move closer to said coil as said core is moved out of said coil; first and second capacitors in series shunted across said inductance device to secure resonance within a first range of frequencies by movement of said core and said conducting plate; and a third capacitor in shunt with said inductance device to secure resonance within a second range of frequencies by movement of said core and said conducting plate, said capacitors being so chosen that any frequency of said second range is higher than the corresponding frequency of said first range by a practically constant amount throughout said core and plate movement.

6. In a superheterodyne radio receiving system an antenna; a vacuum tube having an input electrode; and elements including a variable inductance device comprising an inductance coil, a movable ferro-magnetic core, and a movable conducting plate arranged to approach said coil as the core is withdrawn therefrom; a first resonant circuit including said inductance device and tunable thereby over a first range of frequencies connected between said antenna and ground; and a second resonant circuit including said inductance device and tunable thereby over a second frequency range in series between said

antenna and said input electrode, said elements being so proportioned that said resonant circuits are maintained at a practically constant frequency difference during movement of said core.

7. An image suppression system for super-heterodyne radio receivers having an antenna and a vacuum tube with a control electrode, including a first resonant circuit, a portion of which is connected between said control electrode and ground; and a second resonant circuit in series between said antenna and said control electrode, said resonant circuits having a common variable inductance device comprising an inductance coil, a ferro-magnetic core movable relatively thereto, and a conducting member mechanically movable with said core and movable toward said coil as said core moves out, said member being tapered to provide an increased rate of capacity change of said coil as it moves toward said coil, said resonant circuits being simultaneously tuned by motion of said core and said plate to a signal frequency and the corresponding image frequency.

8. An image suppression system for super-heterodyne radio receivers having an antenna and a vacuum tube with a control electrode, including a first resonant circuit, a portion of which is connected between said control electrode and ground; and a second resonant circuit in series between said antenna and said control electrode, said resonant circuits having a common variable inductance device comprising an inductance coil, a ferro-magnetic core movable relatively thereto; and a conducting sleeve movable with said core relatively to said coil to vary the distributed capacity thereof, and being movable in a direction to increase the distributed capacity thereof with reduction of the inductance thereof, said resonant circuits being simultaneously tuned by motion of said core and said plate to a signal frequency and to the corresponding image frequency.

9. An image suppression system for super-heterodyne radio receivers having an antenna and a vacuum tube with a control electrode, including a first resonant circuit, a portion of which is connected between said control electrode and ground; and a second resonant circuit in series between said antenna and said control electrode,

said resonant circuits having a common variable inductance device comprising an inductance coil, a ferro-magnetic core movable relatively thereto; and a conducting sleeve movable with said core relatively to said coil to vary the distributed capacity thereof, and being movable in a direction to increase the distributed capacity thereof with reduction of the inductance thereof, said sleeve being tapered in developed form in a manner to increase the rate of change of distributed capacity as said sleeve moves toward said coil, said resonant circuits being simultaneously tuned by motion of said core and said plate to a signal frequency and to the corresponding image frequency.

10. Tuning mechanism comprising, in combination, a coil, a ferro-magnetic core movable into and out of said coil, and a conducting plate mechanically connected to said core and movable toward said coil as the core moves out said plate being split so as to minimize the inductance-changing effect thereof.

11. Tuning mechanism comprising, in combination, a coil, a ferro-magnetic core movable into and out of said core, and a conducting plate mechanically connected to said core and movable toward said coil as said core moves out, said plate being tapered to provide a greater rate of change of capacity as it moves toward said coil said plate being split so as to minimize the inductance-changing effect thereof.

12. Tuning mechanism comprising, in combination, a coil, a ferro-magnetic core movable into and out of said coil, and a conducting sleeve mechanically connected to said core and movable toward said coil as said core moves out said sleeve being split so as to minimize the inductance-changing effect thereof.

13. Tuning mechanism comprising, in combination, a coil, a ferro-magnetic core movable into and out of said coil, a conducting sleeve mechanically connected to said core for movement toward said coil as said core moves out, said sleeve being tapered in developed form whereby the rate of change of capacity increases as said sleeve moves toward said core said sleeve being split so as to minimize the inductance-changing effect thereof.

FREDERICK H. SCHEER.
